TYPE BAR ACTION FOR TYPEWRITING MACHINES

Claude T. Rice, Brooklyn, N. Y.

Application July 26, 1947, Serial No. 763,947

6 Claims. (Cl. 197—30.)

1

This invention relates to writing machine or typewriter actions in general, and more especially to silent or noiseless typewriter actions, this application constituting a continuation in part of my co-pending application, Ser. No. 686,620, filed July 27, 1946.

Among the objects of the present invention it is aimed to provide an improved silent typewriter action including an actuating key, a type bar and a connecting mechanism which effects a variable motion including an accelerated initial motion, a decelerated second motion after the type head of the type bar selected has been brought into printing position, and then a third motion resulting from the momentum generated by the initial motion simulating a pressure blow as distinguished from a striking blow.

More specifically, the present invention aims to provide an improved typewriter action using a toggle linkage to generate an initial accelerated motion, a second decelerated motion when the toggle linkage approaches dead center, and a third motion resulting from the momentum generated by the initial motion to enable said toggle linkage to pass dead center and while doing so bring into action a decelerating medium.

These and other features, capabilities and advantages of the present invention will appear from the subjoined detail description of specific embodiments thereof illustrated in the accompanying drawings, in which

Figs. 1 and 2 illustrate successive positions in side elevation of one embodiment.

Figs. 3 and 4 illustrate successive positions in side elevation of a second embodiment.

In the embodiment illustrated in Figs. 1 and 2, the platen 1 is illustrative of the class of platens in which the platen is shifted to receive the upper case characters, being illustrated in its descended, normal position, to receive lower case characters. The type bar 2 is pivotally mounted on the fixed pin or shaft 3, being provided with a head 4 having a lower case character 5 and an upper case character 6. The key bar 7, illustrative of the conventional key bar, is pivotally mounted at one end on the fixed pin or shaft 8, and at its other end provided with a conventional key 9.

In the interest of an understanding of the operation of this embodiment and to show its relation to the other embodiment hereinafter to be described, it is here to be noted that in both embodiments there are only four fixed pivot pins, such as the pivot pins 3 and 8 aforesaid and the pivot pins 10 and 23 hereinafter to be described.

2

The pivot pin 10 extends through the angle or bend in the bell crank lever or bent lever 11, which has a broad arm 12 and a long arm 13. The arm 12 has connected thereto the tension spring 14 for maintaining the typewriter action at rest and in turn for returning the typewriter action to normal position or position of rest after actuation thereof in accordance with convention.

The long arm 13 forms a toggle linkage with 10 the link 15, the action of which constitutes an important, if not the main, feature of the present invention. The link 15 is pivotally connected at one end to the free end of the arm 13 and at its other end is pivotally connected to the short link 16 constituting a part of the control for the type bar 2. The link 15 is fulcrumed or pivoted intermediate its ends to the upper end of the link 17 constituting another part of the control for the type bar 2, the lower end of which link 17 is pivotally connected to the short arm or extension 18 integral with the type bar 2.

The link 15 functionally is divided into two arms 19 and 20, the arm 19 cooperating with the arm 13 to form a toggle linkage, the movement of 25 which from the dotted line position shown in Fig. 1 toward the full line position shown in Fig. 1, upon actuation effecting an accelerated, rapid initial motion, the movement of which when approaching and passing the dead center, the full line position shown in Fig. 1, being decelerated, and the motion of which from the full line position of Fig. 1 to the full line position in Fig. 2 simulating a pressure blow as distinguished from a striking blow to effect a silent or noiseless printing impression by the type bar 2.

To aid in effecting a uniform pressure blow by a plurality of actions, and in properly positioning the type bar 2 preparatory to an actuation, preferably there is provided a stop 21 which, in 40 the present instance, is positioned to engage the rear face of the type head 4 of the type bar 2, as shown in the dotted line position of Fig. 1.

Furthermore, to limit the arm 13 of the lever 11 in the final printing position of the type bar 2 45 and thereby prevent any repeat printing action by the type bar 2, preferably a second stop 22 is provided, in the present instance positioned to engage the upper edge of the arm 13 in the printing position of the type bar 2.

The key bar 7 in the present instance cooperates with the link 17 and type bar 2 to effect a deceleration of the type bar 2 as it moves through its third motion, and also to effect initial actuation of the type bar 2. The key bar 7 is pivotally connected intermediate its ends to one end

of the link 24, the other end of which is pivotally connected to one arm 25 of the bell crank 26, pivoted on the pivot pin 23, the other arm 27 of which bell crank 26 is pivotally connected at its free end to one end of the link 28, the other end of which link 28 is connected to the free end of the short arm 18. In this embodiment it will be seen that the link 17 is pivotally connected to the short arm or extension 18 intermediate its free end and the pivot pin 3.

The embodiment illustrated in Figs. 3 and 4 is substantially identical to the embodiment illustrated in Figs. 1 and 2 except that the key bar 29 is pivotally connected intermediate its ends to one end of the link 30, the other end of which link 30 is connected to the arm 31 of the bell crank lever 32 which is pivoted on the fixed pivot pin 33. The free end of the other arm 34 of the bell crank lever 32 is pivotally connected to one end of the link 35, the other end of which link 35 is pivotally connected to the free end of the arm 36 of the link 37 which takes the place of the link 17 illustrated in the embodiment of Fig. 1. The link 37 is pivotally connected intermediate its long arm 38 and its short arm 36 to the free end of the short arm or extension 39 of the type bar 40. The embodiment illustrated in Figs. 3 and 4, therefore, differs from the embodiment illustrated in Figs. 1 and 2, primarily in that the key bar 29 through the linkage 30, 32 and 35 is connected to the free end of the link 37, whereas the key bar 7 of the embodiment illustrated in Fig. 1 is connected by the linkage 24, 26 and 28 to the free end of the extension or short arm 18 of the type bar 2 and not directly connected to the link 17.

In both embodiments, however, it will appear that there is a restraining action exercised on the toggle linkage formation by the key bar and its associated linkage when the toggle linkage formation executes its third motion, that is, to and beyond dead center.

In the embodiment illustrated in Figs. 3 and 4, the key bar 29 cooperating with the linkage 30, 32 and 35 positively opposes the movement of the arm 41 and link 42 from the full line position shown in Fig. 4 into the dash and dot line position shown in Fig. 4, thereby to restrain the action when executing its third motion or printing action.

This restraining action is effected, as aforesaid, either by directly or indirectly connecting the extension or short arm of the type bar with the key bar. In the embodiment illustrated in Figs. 1 and 2, the key bar 7 is connected by the linkage 24, 26 and 28 to the short arm or extension 18 while in the embodiment illustrated in Figs. 3 and 4, the key bar 29 is connected by the linkage 30, 32, 35 and 36 to the short arm or extension 39 of the type bar 40.

From the foregoing it will appear that in the embodiment illustrated in Figs. 1 and 2, the arm 13, links 15, 16 and 17 and type bar 2 may conveniently be grouped as one linkage for controlling the type head 4, while moving into printing position, and that the key bar 7, linkage 24, 26 and 28 and short arm 45 of the extension 18 may be grouped as the second linkage for initiating the actuation of the mechanism. Similarly in the embodiment illustrated in Figs. 3 and 4, the arm 41, links 42, 43, arm 38 and type bar 40 may conveniently be grouped as one linkage for controlling the type head 44, and the key bar 29, linkage 30, 32 and 35 and arm 36 of the link 37

may be conveniently grouped as the second linkage for initiating the actuation of the mechanism.

It is obvious that various changes and modifications may be made to the details of construction without departing from the general spirit of the invention as set forth in the appended claims.

I claim:

1. The combination with a platen, of a key bar pivotally mounted on a fixed pivot, a first linkage including a type bar having a head at one end and pivotally mounted on a fixed pivot, a lever fulcrumed on a fixed pivot, a spring connected to one arm of said lever for normally maintaining said linkage in position of rest and for restoring it to position of rest, a first link pivotally connected at one end to the free end of the other arm of said lever, a control including a first means and a second means, said first means extending from said type bar adjacent its pivot to said first link and pivotally connected to said first link intermediate its ends, said second means operatively associating the other end of said first link with said type bar adjacent its head to vary the distance between said head and said other end of said link as the head is moved into and out of printing relation to said platen, and a second linkage operatively connected at one end to said key bar and at its other end to said type bar to actuate said first linkage and therewith said type bar into printing relation with said platen when said key bar is actuated in opposition to said spring, said lever and first link forming a toggle action and when actuated by said key bar executing an initial accelerated motion before reaching dead center and thereupon executing a decelerated motion when passing dead center.

2. The combination with a platen, of a key bar pivotally mounted on a fixed pivot, a first linkage including a type bar having a head at one end and pivotally mounted on a fixed pivot, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including a first means and a second means, said first means extending from said extension to said first link and pivotally connected to said first link intermediate its ends, said second means operatively associating the other end of said first link with said type bar adjacent its head to vary the distance between said head and said other end of said link as the head is moved into and out of printing relation to said platen, and a second linkage operatively connected at one end to said key bar and at its other end to said extension to actuate said first linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion when passing dead center.

3. The combination with a platen, of a key bar pivotally mounted on a first fixed pivot, a first linkage including a type bar having a head at one end and pivotally mounted on a second fixed pivot, said type bar having an extension beyond its fixed pivot, a lever fulcrumed on a third fixed pivot, a spring connected to one arm of said

lever for normally maintaining said first linkage in position of rest and for restoring it to position of rest, a first link pivotally connected at one end to the free end of the other arm of said lever, a control including a first means and a second means, said first means extending from said extension to said first link and pivotally connected to said first link intermediate its ends, said second means operatively associating the other end of said first link with said type bar adjacent its head, a second linkage operatively connected at one end to said key bar and at its other end to said first means to actuate said first linkage and therewith said type bar into printing relation with said platen when said key bar is actuated in opposition to said spring, said lever and first link forming a toggle action and when actuated by said key bar executing an initial accelerated motion before reaching dead center and thereupon executing a decelerated motion when passing dead center.

4. The combination with a platen, of a key bar pivotally mounted on a first fixed pivot, a first linkage including a type bar having a head at one end and pivotally mounted on a second fixed pivot, said type bar having an extension beyond its fixed pivot, a first lever fulcrumed on a third fixed pivot, a spring connected to one arm of said lever for normally maintaining said first linkage in position of rest and for restoring it to position of rest, a first link pivotally connected at one end to the free end of the other arm of said lever, a control including a second lever and a second link, one arm of said second lever extending from said extension to said first link and pivotally connected to said first link intermediate its ends, said second link operatively associating the other end of said first link with said type bar adjacent its head, and a second linkage operatively connected at one end to said key bar and at its other end to the other arm of said second lever to actuate said first linkage and therewith said type bar into printing relation with said platen when said key bar is actuated in opposition to said spring, said first lever and first link forming a toggle action and when actuated by said key bar executing an initial accelerated motion before reaching dead center and thereupon executing a decelerated motion when passing dead center.

5. The combination with a platen, of a key bar pivotally mounted on a fixed pivot, a first linkage including a type bar having a head at one end and pivotally mounted on a fixed pivot, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including a first means and a second means, said first means ex-

tending from said extension to said first link and pivotally connected to said first link intermediate its ends, said second means operatively associating the other end of said first link with said type bar adjacent its head, a second linkage operatively connected at one end to said key bar and at its other end to said extension to actuate said first linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion when passing dead center, said second linkage including a bell crank mounted on a fixed pivot, a second link operatively connecting one arm of said bell crank with said key bar, and a third link operatively connecting the other arm of said bell crank with said extension.

6. The combination with a platen, of a key bar pivotally mounted on a first fixed pivot, a first linkage including a type bar having a head at one end and pivotally mounted on a second fixed pivot, said type bar having an extension beyond its fixed pivot, a first lever fulcrumed on a third fixed pivot, a spring connected to one arm of said lever for normally maintaining said first linkage in position of rest and for restoring it to position of rest, a first link pivotally connected at one end to the free end of the other arm of said lever, a control including a second lever and a second link, one arm of said second lever extending from said extension to said first link and pivotally connected to said first link intermediate its ends, said second link operatively associating the other end of said first link with said type bar adjacent its head, a second linkage operatively connected at one end to said key bar and at its other end to the other arm of said second lever to actuate said first linkage and therewith said type bar into printing relation with said platen when said key bar is actuated in opposition to said spring, said first lever and first link forming a toggle action and when actuated by said key bar executing an initial accelerated motion before reaching dead center and thereupon executing a decelerated motion when passing dead center, said second linkage including a bell crank pivotally mounted on a fourth fixed pivot, a third link operatively connecting one arm of said bell crank with said key bar, and a fourth link operatively connecting the other arm of said bell crank with the other arm of said second lever.
